Specification for Design.

Patented Apr. 26, 1921.

Application filed September 7, 1920. Serial No. 408,789. Term of patent 14 years.

To all whom it may concern:

Be it known that I, ELMER E. SWIHART, a citizen of the United States, and a resident of Seattle, in the county of King and State of Washington, have invented a new, original, and ornamental Design for a Combined Kitchen-Reminder and Advertising-Chart, of which the following is a specification, reference being had to the accompanying drawings, forming part thereof.

The figure is an elevation of a combined kitchen reminder and advertising chart, showing my new design.

I claim:

The ornamental design for a combined kitchen reminder and advertising chart, as shown.
